ROLLER DRIER

Arthur H. Beckley, Jr., Portland, Oreg., assignor
to The Moore Dry Kiln Company of Oregon,
a corporation

Application March 2, 1942, Serial No. 432,954

8 Claims. (Cl. 34—205)

My invention relates to improvements in roller driers in which work, such as veneer or other flat material to be dried, is progressed between driven rolls on several decks simultaneously from one end of the drier to the other.

Due to the high temperature at which this drier operates it is desirable that working parts of the drier be quickly and individually demountable.

An object of my invention is to provide novel means for mounting the rolls, coil heaters, and roll bearing in relation to doors so they are quickly and individually demountable without disturbing the other parts of the drier.

Another object of my invention is to provide a quickly demountable construction to aid in cleaning out and repairing the drier.

What constitutes my invention hereinafter will be described in detail and succinctly defined in the appended claims.

In the accompanying drawings wherein my invention is illustrated in preferred form of embodiment,

Figure I is a side elevation of a drier constructed in accordance with this invention.

Figure II is a plan view of the drier shown in Figure I.

Figure III is a partial cross section along the lines III—III of Figure I.

Figure V is a partial horizontal cross section of a door with its frame showing a hinge and door latch.

Figure V is a diagrammatic perspective drawing showing the arrangement of bearing plates in relation to the frame and the drier sections.

Figure VI is a side elevation of the frame anchor, enlarged to show the details.

Figure VII is a partial side elevation on an enlarged scale, showing a portion of the drier, with part of the door cut away to show details of the interior construction.

Figure VIII is a partial plan view of a drier coil with headers cut away to show the steam flow through the coil.

Figure IX is a partial section along the lines XIII—XIII of Figure VII showing the bearing plate, bearing and drive in detail.

Figure X shows an alternate construction for mounting the roll bearings and rolls.

Figure XI is a partial cross section along the lines XI—XI of Figure X.

Referring to the numerals of the drawings, like numbers illustrate corresponding parts.

The drier is constructed of substantially duplicated sections throughout the length of the drier, and each section is made mostly of duplicated

parts. Of these sections, 1 indicates the outer vertical channels, and 2 the horizontal roof beams which connect the tops of the vertical channels 1, disposed on opposite sides of the drier. Intermediate vertical angles 3, are in pairs back to back on each side of the drier frame and extend from the roof beam 2 down to and connected with the horizontal channels 4 which extend from near the bottom of plate 5 on one side of the drier to the plate 5 on the opposite side of the drier near its bottom end. The vertical channels are attached respectively to the vertical plates 5 which are attached to the vertical angles 3 by the connecting straps 8, and to the horizontal channels 15 by the gussets 9.

A series of horizontal bearing plates 11, extend longitudinally between the vertical angles 3 from one section to another, on each side of the drier. They have openings 10 for receiving the bearing housings 10, which openings are large enough for the bottom rolls 66 to pass through them, when the bearing housings 10 are removed.

Longitudinal bottom frame angles 12 are attached to the bottom end of the vertical channels 1 and vertical plates 5 and extend the full length on each side of the drier, and rest upon, without attachment to, the filler strip 13 the full length of the drier. These filler strips 13 are bolted to the ground or floor through the longitudinal floor angles 15 which extend the full length of the driers and which, with the filler strip 13, comprise a track on which the frame angles 12 slide when longitudinal expansion and contraction of the drier occurs. The filler strip 13 and the floor angles 15 are anchored by flat head countersunk machine bolts 14 in the anchors 16 which are preferably set into the concrete floor or ground. Transverse clearance between the angles 12 and 15 is small and drier expansion or contraction occurs without causing mis-alignment of the drier frame, and the consequent feeding of work to one side or the other as it passes through the drier.

The bearing plates 11 are bolted to the vertical angles 3 employing bolts which closely fit the holes. All longitudinal frame members including the bearing plates 11 are carefully made, accurate in length, and are mounted in such manner that both sides of the drier frame expand and contract equally, when heated and cooled. The bearing plates 11 are made in different lengths, some one section in length, and some two sections in length. The bearing plates are mounted in staggered relationship considering the same deck on the two sides of the drier and in staggered

relationship vertically on each side of the drier, preferably as illustrated in Figure V.

There is a particular and peculiar benefit derived from using bearing plates 11 of different lengths as illustrated in Figure V. This design is employed to insure the accurate spacing of the vertical angles, on each side of the drier. If the bearing plates in one section stopped at a single set of vertical angles there might be a possibility of a loose joint between the two angles of the set and one side of the drier being longer than the other. It is essential that both sides of the drier be of equal length to insure the veneer passing through the drier, in a straight line, and not creeping to one side as it passes between the rolls through the drier. By staggering the lengths of the bearing plates and squaring up the drier frame it would be substantially impossible for one side of the drier to be longer than the other or for the rolls to be at any other angle than right angles to the bearing plates, on each side of the drier, of course, considering that the bearing plates were fabricated with the necessary uniform spacings of holes for attachment to the vertical angles.

Top angles 18 extend longitudinally on each side of the drier, connecting the ends of horizontal roof beams 2 and the plates 5 on the two outer edges of the drier. These angles 18 support the longitudinal roof angles 20 which confine the outer edge of the panels of the drier.

I provide a center anchor 55 near the center, one anchor on each side of the drier. Each anchor is attached to a horizontal channel 4 and to the ground or floor so that creep due to longitudinal expansion or contraction of the drier frame occurs in two directions from this anchor.

Door seals 23 are bolted to the inner side of and near the edge of the vertical plates 5 and of the longitudinal angles 12 and 18 through the strap 24 which provides a backing for the door seals 23.

Doors 26 are made of insulated metal panels 25 imperforate on the inside as illustrated in Figure IV. They are carried by hinges 27, and are fastened by latches 28 on the door and catches 29, attached to the vertical angles 1. The latches 28 are attached to the door inner frame 30 from the outside surface of the door only and no bolts extend through inner surface of the panel 25. The door frame 30 is rigidly welded together of structural steel shapes to which the hinges and latches are attached through the outside metal surface only of the door. The metal sheet covering the inside of the panel is seamless, and is bent over the frame 30 forming seams on the outside surface only which permits moisture to escape or enter the panel only from the outer or colder side.

The roof of the drier is covered by panels 31 which rest upon the horizontal roof beams 2. The panels 31 are joined together by the clamping action of battens 34, which have stud bolts 36 attached to them, as illustrated in Figure III. The top battens 37 have holes through which the stud bolts 36 pass and on which nuts are screwed to clamp the battens and adjacent panels together, to give a tight insulated housing for the drier yet allow some movement in expansion and contraction.

A longitudinal duct 40 is provided on top of the drier at each of its ends for recirculating and reheating the drier atmosphere. Two fans 42 at each end of the drier suck drier atmosphere through the suction manifold doors 44 through

the transition ducts 45 and discharge the atmosphere into the duct 40 which is bifurcated at the end opposite the fan, and the atmosphere passes through two banks of reheaters 48 and is discharged through slots 49 in the two manifold doors 50 back into the drier.

The duct panels 32 and the roof panels 31 are similar in construction. They have an inner frame 41 to prevent the panel from being crushed when walked upon. The panel is imperforate on the inside surface so that no moisture can enter it from the inside of the drier. The panel is not sealed tight on the outside surface due to cracks or bolt holes so that any moisture in the insulation material can escape when the panel 31 is heated, and thus prevent corrosion to the inner surfaces of the metal panels. The corners are welded tight and the outer edge may be seamed.

Some of the panels have bars 38 attached to the panel frames 41 in such position that cap screws 35 can be screwed into the bars 38 from the outside surface of the panels. Here the duct panels 32 are attached to the roof panels 31 by means of a strap 39 which is spot welded or otherwise attached to the edge of the panels 31 or 32. The cap screws 35 pass through the strap 39 and into the bar 38 of the roof panel adjacent to it. A gasket 60 is placed between the edge of the duct panel strap 39 and above the bar 38 of the roof panel to insure tight closure when the cap screw 35 is tightened.

The atmosphere recirculating system at the green end preferably sucks atmosphere from the green end of the drier and discharges it to the center through reheaters 48. The fans 42 at the dry end suck atmosphere from the dry end and discharge it through the reheaters 48 to the center of the drier. Stacks 53 are provided with dampers 54 and may vent excess drier atmosphere from the recirculation duct before it passes across the reheaters 48.

Bearing housings 70 are inserted into the openings 80 in the bearing plates 11 and are attached to the bearing plates by two cap screws 45 33. The bearing housings 70 have a shoulder, which fits snugly into the opening of the bearing plate 11. The opening 80 of the bearing plate is large enough to permit the roll 66 to be passed through it at will by removing the bearing housing 50.

The bearing housings are bored out large enough to accommodate loose rollers 73 on which the gudgeon shaft 68 rotates. A cap 22 on the ends of the bearing housing 70 holds the rollers 55 73 in the bearing and retains lubrication which is injected by an Alemite gun through the Alemite fitting 71 and oil hole as illustrated in Figures IX and X.

The top rolls 67 have gudgeons 68 in their 60 ends and lay in a semi-loose position directly on top of the bottom rolls 66 so that the bottom roll and top roll are a pair driven in opposite directions of rotation for conveying the work through the drier. The bottom roll 66 is driven about a 65 fixed axis by a sprocket 77 and chain 79 on one side of the drier. The bottom roll has a star gear 85 on the end which is opposite the sprocket and which intermeshes with the star gear 85 of the top roll. The star gears have teeth of sufficient length to permit a vertical movement of the top rolls which rotate about a variable axis to accommodate different thicknesses of work passing between and being driven by top and bottom rolls through the drier. The star gears 70 75 at one end of the top and bottom rolls are inter-

meshed in such a manner that the top roll is always driven by the bottom roll in reverse direction of rotation so that the work is propelled by rotation of the rolls from one pair of rolls to another on each deck as it passes through the drier from its green to its dry end.

The rolls of each of the decks of the drier have a separate chain driving them. The chains 19 for each of the decks are driven preferably by a common reduction gear 82, driven at varying speeds by variable drive, such as a Reeves drive 83 which in turn is driven by an electrical motor 84. The gear 82 has a driver gear 86 for each of the decks, each of which can be driven at the same speed or at different speeds by having a different number of teeth for the driver gear for the particular deck. The gear 82 is located at the dry end of the drier so that the chains are drawn through in driving the rolls engaging the top teeth of the sprockets 71. A weight chain take-up 89, comprising individual weights for each chain 19 or any suitable means for maintaining tension on each chain may be used such as that illustrated in Patent No. 1,523,988.

A feed section is provided at the green end of the drier, having a bed of single rolls 66 and a feed roll arrangement as illustrated in Figures I and II.

Attention is called to application, Serial No. 430,103, in which claims applying to some of the matter described in this application are made.

The heating system in the drier consists of a plurality of easily demountable coils in each drier section on each side of each pair of rolls as illustrated in Figure VII. Each coil consists of a pair of pipes fed together and which are returned back and fourth a number of times throughout the extent of the coil having their interiors connecting at each header. By feeding two pipes together and returning these throughout the coil, the steam travel is one half as great as if one pipe return coil were used. I employ feed and drain headers 101 which have two pipes 105 connected to them, and return headers 103, which have four pipe connections, two entering and two leaving them. These headers have the pipes preferably welded to them in such manner that two lines of pipe connect opposite headers and conduct condensate from the feed header to the drain header of each coil.

The headers are each attached by two stud bolts 106 to clips 111 of varying lengths attached to the angles 107 which loosely hold them as a unit and allow for expansion and contraction of the coil and yet prevent it from spreading. The varying lengths of the clips incline the coil at a slight angle from the horizontal to provide drainage in the coil. The outside clips of each angle have slotted holes 112 to permit reducing the coil width, to facilitate dismantling and assembly of it. These angles 107 are attached rigidly to bearing plates 11 by cap screws 108 adding stability to the bearing plates. Each coil is connected by two unions 64 to the feed and drain manifolds and when these unions are disconnected, and the angles 107 unbolted, the coils may be reduced in width by the amount of play of the studs 106 in the holes 112 and taken out of the drier and replaced through the door opening.

The steam feed manifold 109 delivers steam from a source not illustrated, to the several coils, two for each deck, one coil above and one below each deck of paired rolls which convey the work through the drier. The drain manifolds 110 col-

lect condensate from each of the coils and deliver it to a return line 113 which goes to the steam trap 114, and then through a check valve 62 into the return main 63.

5 I show an alternate construction of a bearing support comprising an angle 56 or other suitable member extending longitudinally between upright angles 3 on each side of the drier. A cast bearing housing 57 is bolted to the top flange of the angle 56. I preferably employ the same coil hanger angles 107 with variable length clips 111, having holes for the stud bolts 106 as described above.

15 As in the preferred construction, either the bearing housings, heating coils or rolls are individually demountable, without removing the bearing plates or the other equipment mentioned, which is a feature of my invention.

20 It is understood that this invention is not limited to the exact design and form illustrated and described. Modifications of the structures and methods herein described and equivalents are self-evident to those skilled in the art; therefore, it is to be understood that the invention includes within its scope whatever changes fairly come within either the terms or the spirit of the appended claims.

25 Having described my invention, what I claim is:

30 1. In a drier of the class described, a sectional drier frame operatively mounted on a drier foundation, said frame comprising vertical members on each side of said drier, horizontal members extending longitudinally at the top and bottom of each side of said frame, other vertical members connected with said horizontal members to form a door jamb, a plurality of apertured horizontal bearing supports extending longitudinally between the first named vertical 35 members on each side of said frame, a plurality of decks of pairs of operatively mounted rolls each pair comprising top and bottom rolls, which are rotated in opposite directions to convey work through said drier, said decks of rolls being supported by said bearing supports, gudgeons with shafts mounted in the ends of said rolls, bearing housings for the gudgeon shafts of said bottom rolls, having guides for the shaft of said top rolls, permitting each of them to rotate about a variable axis, said bearing housings being detachably mounted on said bearing supports and extending into said apertures, heating coils in 40 units, coil supporting members, one on each end of said coil, said coil supporting members having means for supporting each end of said heating coils, whereby said bearing housings, rolls, coil supports and coil units are individually demountable and removable from said drier between said door jambs without removing said bearing supports.

45 2. In a drier of the class described, a sectional drier frame operatively mounted on a drier foundation, said frame comprising vertical members on each side of said drier, a plurality of horizontal bearing plates extending longitudinally between said vertical members on each side of said frame, a plurality of decks in said drier each comprising a series of operatively mounted transverse rolls in pairs of top and bottom rolls which 50 are rotated in opposite directions to convey work through said drier, said decks of rolls being operatively mounted in bearings demountably supported by said bearing plates, gudgeons with shafts mounted in the ends of said rolls, bearing 55 housings for the gudgeon shafts of said bottom 60 rolls, having guides for the shaft of said top rolls, permitting each of them to rotate about a variable axis, said bearing housings being detachably mounted on said bearing supports and extending into said apertures, heating coils in units, coil supporting members, one on each end of said coil, said coil supporting members having means for supporting each end of said heating coils, whereby said bearing housings, rolls, coil supports and coil units are individually demountable and removable from said drier between said door jambs without removing said bearing supports.

65 3. In a drier of the class described, a sectional drier frame operatively mounted on a drier foundation, said frame comprising vertical members on each side of said drier, a plurality of horizontal bearing plates extending longitudinally between said vertical members on each side of said frame, a plurality of decks in said drier each comprising a series of operatively mounted transverse rolls in pairs of top and bottom rolls which 70 are rotated in opposite directions to convey work through said drier, said decks of rolls being operatively mounted in bearings demountably supported by said bearing plates, gudgeons with shafts mounted in the ends of said rolls, bearing 75 housings for the gudgeon shafts of said bottom rolls, having guides for the shaft of said top rolls, permitting each of them to rotate about a variable axis, said bearing housings being detachably mounted on said bearing supports and extending into said apertures, heating coils in units, coil supporting members, one on each end of said coil, said coil supporting members having means for supporting each end of said heating coils, whereby said bearing housings, rolls, coil supports and coil units are individually demountable and removable from said drier between said door jambs without removing said bearing supports.

rolls, said bearing housings having guides for the shafts of said top rolls permitting them to rotate about a variable axis, said bearing plates having a series of openings for the accommodation of said bearing housings, said openings being larger than the diameter of said bottom rolls, whereby said bearing housings and bottom rolls may be removed from the drier without removing said bearing plates.

3. In a drier of the class described, a sectional drier frame operatively mounted on a drier foundation, said frame comprising vertical members on each side of said drier, a plurality of horizontal apertured bearing supports, extending longitudinally between vertical members on each side of said frame, a plurality of decks in said drier each comprising a series of operatively mounted transverse rolls in pairs of top and bottom rolls which are rotated in opposite directions to convey work through said drier, said decks of rolls being supported by said bearing supports, gudgeons with shafts mounted in the ends of said rolls, bearing housings, detachably mounted on, and extending into the apertures of said bearing supports for the gudgeon shafts of said bottom rolls, said apertures being larger in diameter than the diameter of said rolls, said bearing housings having guides for the shafts of said top rolls permitting them to rotate about a variable axis, said bearing supports having means for attachment of said bearing housings, whereby said bearing housings and rolls may be removed from the drier without removing said bearing supports.

4. In a drier of the class described, a sectional drier frame operatively mounted on a foundation, said frame comprising in part vertical members on each side of said drier, a longitudinal bottom member on each side of said drier to which the vertical members are attached, horizontal members connecting said vertical members at their top and near their bottom ends, other vertical members on each side of said drier attached to the horizontal members, a plurality of longitudinal bearing plates on each side of said frame mounted on said second named vertical members, some of said plates extending one section long between said adjacent vertical members and others extending a plurality of sections long, said bearing plates being staggered in length with other bearing plates on the drier frame, a track attached to the foundation, said bottom member resting on said track and aligned by it, and an anchor for said frame on each side of the drier near the center of said frame.

5. In a drier of the class described, a sectional drier frame operatively mounted on a foundation, said frame comprising in part vertical members on each side of said drier, a longitudinal bottom angle on each side of said drier to which the vertical members are attached, horizontal members connecting said vertical members at their top and near their bottom ends, other vertical members on each side of said drier attached to the horizontal members, a plurality

of longitudinal bearing plates on each side of said frame mounted on said second named vertical members, some of said plates extending one section long, and others extending two sections long,

5 between adjacent vertical members said bearing plates being staggered in length, with other bearing plates of the drier frame, a track attached to the foundation, said bottom member resting on said track and aligned by it, and an anchor for said frame on each side of the drier near the center of said frame.

6. In a roller drier of the class described, a drier frame, a series of longitudinal bearing plates attached to said frame, some of said bearing plates being staggered in placement with other of said bearing plates, detachable bearing housings, said bearing plates having a series of openings for the accommodation of said housings, each of said housings having a circular portion which fits into the openings in said plates, top and bottom rolls operatively mounted to rotate in opposite directions, gudgeon shafts in said rolls, the shafts of said bottom rolls being mounted in the bearing housings, said openings being big enough for passing said bottom rolls through them, and said bearing housings having guides for the shafts of said top rolls permitting them to rotate about variable axes.

7. In a roller drier of the class described, a drier frame section comprising vertical members, a series of substantially horizontal bearing plates attached to said members, demountable bearing housings, said bearing plates having a series of substantially uniformly spaced openings for the accommodation of said bearing housings, said housings having shoulders which fit into the openings in said plates, top and bottom rolls in pairs operatively mounted for rotation in opposite directions, gudgeon shafts in said rolls, the shafts of said bottom rolls being mounted in said bearing housings, and said openings being big enough for passing one of the said bottom rolls through them.

8. In a drier of the class described, a sectional drier frame operatively mounted on a foundation, said frame comprising in part vertical members on each side of said drier, a longitudinal bottom angle on each side of said drier, to which said vertical members are attached, horizontal members connecting said vertical members at their top and near their bottom ends, other vertical angles on each side of said drier attached to horizontal members, a plurality of substantially horizontal bearing supporting members, on each side of said frame mounted on said second named vertical angles, said bearing supporting members being so placed on each side of said frame, that the end to end meeting of adjacent bearing supporting members at different levels occurs on different vertical angles, a track attached to the foundation, said bottom member resting on said track and aligned by it, and an anchor for said frame to said foundation on each side of the drier near the center of said frame.

65 ARTHUR H. BECKLEY, JR.
